UNITED STATES PATENT OFFICE.

EDGAR H. BERRY, OF ILION, NEW YORK, ASSIGNOR TO WYCKOFF, SEAMANS & BENE-DICT, OF ILION, NEW YORK, A CORPORATION OF NEW YORK.

TYPE-WRITING MACHINE.

937,409.

Specification of Letters Patent.

Patented Oct. 19, 1909.

Application filed September 25, 1907. Serial No. 394,522.

To all whom it may concern:

Be it known that I, EDGAR H. BERRY, a citizen of the United States, and resident of Ilion, in the county of Herkimer and State 5 of New York, have invented certain new and useful Improvements in Type-Writing Machines, of which the following is a specification.

My invention relates to typewriting machines and more particularly to detachable front shields therefor, and the principal object of said invention is to provide a simple and efficient construction of the character specified which can be readily detached from 15 the machine and replaced when desired.

To the above and other ends which will hereinafter appear, my invention consists in the features of construction, arrangements of parts and combinations of devices hereinafter described and particularly pointed out in the appended claims.

In the drawings I have shown only so much of a typewriting machine as is necessary to an understanding of my invention.

Figure 1 is a fragmentary front elevation with parts broken away showing a portion of a typewriting machine with the front shield of my invention mounted in place. Fig. 2 is an enlarged detail sectional view 30 showing a portion of the shield, the section being taken on the line $x-x$ of Fig. 1 and looking in the direction of the arrow at said line. Fig. 3 is a transverse sectional view of the same taken on a line $y-y$ of Fig. 2 35 and looking in the direction of the arrow at said line. Fig. 4 is a vertical sectional view taken on the line $z-z$ of Fig. 1 and looking in the direction of the arrow at said line. Fig. 5 is an enlarged detail sectional view 40 showing one of the spring clips and the engaging device or pin with which it co-operates.

I have shown my invention applied to a front-strike typewriting machine to which 45 it is more particularly adapted, though from certain aspects of the invention it may be employed in other styles of machines.

The framing of the machine comprises corner posts 1 and a top plate 2. A segment 3 is supported by the frame of the machine in any suitable manner and is provided at the upper side thereof with a type rest or pad 4 on which the forward ends of 50 the type bars 5 are supported. This seg-

ment may support certain of the type bar 55 actuating means not shown.

A front shield, designated as a whole by the reference numeral 6, is preferably made of sheet metal and has an outline such as that shown in Fig. 1 and comprises a segmental or arc-shaped portion 7 and a depending portion 8. The central transverse section of this shield is shown in Fig. 4 and it will be seen that the segmental portion 7 extends up in front of the free ends of the 60 type bars and the depending portion 8 there-of projects down below the segment. The shield as a whole covers the segment 3 and the parts which may be carried thereby. Spring clips or catches 9 are each in the nature of a leaf-spring riveted at one end to the rear side of the shield as shown at 10 and the free end projects upwardly and is bent as indicated at 11 to form an engaging 65 portion which co-operates with an engaging 70 device 12 which projects from the segment. The engaging devices 12 are in the nature 75 of pins which are each threaded at one end and screwed into a tapped opening in the segment. In order to attach the shield in 80 place it is merely necessary to place it just below the position it is to assume in the machine and force it upwardly until the upper ends thereof abut the bottom of the top plate and the portions 11 of the spring 85 catches will engage the pins 12, holding the shield in place. The depending portion 8 of the shield has a portion 13 which is inclined downwardly toward the front of the 90 machine and is slotted substantially throughout its length as at 14 to provide an opening through which the indices 15 on an index plate or sheet 16 may be inspected 95 through a transparent covering or sheet 17 of celluloid or like material. The indices 15 are illustrated in Fig. 2 but have been omitted in Fig. 1. The sheets 16 and 17 are secured in place at the back of the inclined portion 13 of the shield by a plate 18 and screws 19, the screws passing freely through 100 openings in the shield and engaging tapped openings in the plate 18 to clamp the sheets 16 and 17 between the rear face of the shield and the plate 18. The inclined portion 13 of the shield is situated above and adjacent 105 to tabulator keys 20 at the rear of the keyboard of the machine so that the indices on the index plate may be read in connection

with said tabulator keys. The inclination of the part 13 which carries the index plate enables the operator to readily observe the indices on the plate and read them in connection with the tabulator keys. By this construction the index for the tabulator is carried by and may be introduced into or detached from the machine with said shield or it may be detached from the shield by the 10 removing screws 19.

Various changes may be made without departing from the spirit and scope of my invention.

What I claim as new and desire to secure 15 by Letters Patent, is:—

1. In a front-strike typewriting machine, the combination of a shield situated in front of the type bars, leaf-springs carried by said shield, and pins which are engaged by said 20 springs for detachably holding the shield in place.

2. In a front strike typewriting machine, the combination of a segment which supports the forward ends of the type bars, engaging devices carried by said segment, a shield situated in front of said segment and in front of the forward ends of the type bars, and spring engaging-devices carried by said shield and coöperative with the 25 engaging devices on said segment for detachably holding the shield in place.

3. In a front-strike typewriting machine, the combination of a segment which supports the forward ends of the type bars, engaging pins projecting from said segment, a shield situated in front of said segment and in front of the forward ends of the type bars, and leaf-spring engaging devices carried by said shield and coöperative with the 30 engaging pins on said segment for detachably holding the shield in place.

4. In a typewriting machine the combination of tabulator keys, a shield detachably secured to the front of the machine, and 45 tabulating index devices carried by and detachable with said shield, said index devices being arranged below the shield and in proximity to the tabulator keys.

5. In a typewriting machine the combination of tabulator keys, a shield detachably secured to the front of the machine, tabulating index devices carried by and detachable with said shield, and means for detachably connecting said index devices to said shield, 55 said index devices being arranged below the shield and in proximity to the tabulator keys.

6. In a typewriting machine, the combination of tabulator keys, a shield detachably secured to the front of the machine, said shield having a portion inclined toward the front of the machine, and tabulator-index devices carried by said inclined portion above the tabulator keys and adjacent thereto.

65 7. In a typewriting machine, the combina-

tion of tabulator keys, a shield detachably secured to the front of the machine, said shield having a portion inclined toward the front of the machine, said inclined portion having a slot that extends transversely of the machine, and tabulator-index devices carried by said inclined portion at the rear side thereof and above the tabulator keys and which may be seen through said slot.

8. In a front-strike typewriting machine, 75 the combination of tabulator keys, a segment for supporting the forward ends of said type bars, a detachably mounted shield situated in front of said segment, said shield having a part which extends transversely of the machine and which is inclined toward the front of the machine and has a slot therein which extends transversely of the machine, and a tabulator index plate secured to the inclined portion of the shield so that it may be seen 80 through said slot, said index plate being arranged above and adjacent to the tabulator keys.

9. In a front-strike typewriting machine, 90 the combination of tabulator keys, a shield situated in front of the forward ends of the type bars, said shield having a depending portion which is slotted, a tabulator index back of the shield and which may be inspected through said slot, the index being arranged above and adjacent to the tabulator keys, and a plate detachably secured to the shield back of said index for holding the 95 index in place.

10. In a front-strike typewriting machine, 100 the combination of tabulator keys, a shield situated in front of the forward ends of the type bars, said shield having a depending portion which is slotted, a tabulator index back of the shield and which may be inspected through said slot, the index being arranged above and adjacent to the tabulator keys, a plate detachably secured to the shield back of said index for holding the index in place, and spring means for detachably holding said shield in place.

11. In a typewriting machine, the combination of tabulator keys, a shield detachably secured to the front of the machine, tabulating index devices carried by and detachable 115 with said shield, said shield having a depending portion which is slotted, a tabulator index back of the shield and which may be inspected through said slot, the index being arranged above and adjacent to the tabulator keys, and a plate detachably secured to the shield back of said index for holding the 120 index in place.

Signed at Ilion, in the county of Herkimer, and State of New York, this 23rd 125 day of September A. D. 1907.
